CLOSURE FOR A RAIL SANDING APPARATUS
Albert G. Dean, Narberth, and Herbert T. Hermann,
Southampton, Pa., assignors to The Budd Company,
Philadelphia, Pa., a corporation of Pennsylvania
Filed July 25, 1962, Ser. No. 212,311
8 Claims. (Cl. 220—32)

This invention relates to sanding apparatus for sanding the rail under a wheel of a railway vehicle, for the purpose of increasing the coefficient of friction between the wheel and the rail.

In general, rail sanding apparatus comprises a sandbox which contains a supply of the sand that is to be deposited on the rail, a nozzle for directing the sand beneath the wheel, and means, such as a pneumatic air valve and control system therefor, for selectively causing sand to flow from the sandbox, through the nozzle and onto the rail beneath the wheel.

In order for the sand to flow properly, it must be kept in a relatively dry condition. However, this is difficult to accomplish because the sandbox is normally exposed to weather elements such as rain, snow, hail and the like whereby such elements can enter the sandbox and contaminate the sand so that it is no longer readily flowable.

Heretofore, it has been customary to fill the sandbox through an opening that is covered by a screw-type cover having threads which, because of the abrasive action of the sand, are subject to galling and deterioration to the extent that weather elements can enter the sandbox even though the cover is in place.

Accordingly, one of the objects of the invention is to provide improved sanding apparatus which can be readily filled but which prevents weather elements from entering the sandbox.

Another object is to provide an improved cover and cover actuating mechanism for a sandbox.

Still another object is to provide improved sanding apparatus wherein a cover is permanently mounted on the sandbox so that the cover cannot be lost readily.

Other objects and advantages will be apparent from the following description taken in connection with the accompanying drawing wherein:

FIG. 1 is a side elevational view of a portion of a railway vehicle embodying the invention;

FIG. 2 is a perspective view, of a sandbox, illustrated in FIG. 1, embodying the invention;

FIG. 3 is a vertical sectional view along lines 3—3 of FIG. 1; and

FIG. 4 is a sectional view on line 4—4 of FIG. 3, FIGS. 2, 3 and 4 being on enlarged scales relative to that of FIG. 1, for clarity of illustration.

Referring now to the drawing, there is illustrated in FIG. 1 a portion of a railway vehicle which portion comprises a car body 10 supported by a truck 12 having a plurality of wheels 14 engaged with the upper surface 16 of a rail. The railway vehicle carries sanding apparatus for sanding one of the rails beneath and ahead of one of wheels 14, such sanding apparatus comprising a sandbox assembly 18 adapted to store a quantity of sand, a nozzle 20 for directing the sand beneath the wheel, a selectively actuatable pneumatic valve 22, and a hose 24 extending between the valve and the nozzle.

As shown in FIGS. 1 and 3, the sandbox assembly 18 is supported by a pair of rear angle brackets 26 and a pair of front brackets 28 beneath the bottom of the car body and inboard of the side sill 30, the front bracket being welded to a Z support 32. Brackets 26 and 28 are secured by bolt and lock nut assemblies 33 so that the sandbox assembly depends from the railway vehicle body in front of the wheel to be sanded.

2

Sandbox assembly 18 comprises a sandbox 34, a cover 36, a cover retaining spring 38, and a throwover lever 40. Sandbox 34 includes a bottom plate 42 having an outlet 44 aligned with the inlet 46 of valve 22, there being a screen 48 extending across and above outlet 44. Sandbox 34 also includes a plurality of panels 50 arranged as shown in the drawing to provide an enclosed chamber for storing the sand that is to be deposited upon the rail. The upper front one of panels 50 is provided with a centrally located opening 52.

Sandbox 34 further includes a pair of mounting flanges 54, and an inverted, frusto-conical funnel 56 secured to panel 50 over opening 52, the axis of the funnel passing through the center of the opening. Funnel 56 is wide at its base and narrow at its top, the top terminating in a circular, annular edge which defines or bounds a circular fill opening through which sand passes as it is being poured into the sandbox.

Cover 36 comprises a circular body 58 and a pair of concentric, axially extending flanges 60 and 62 spaced apart to define an annular groove within which is secured an annular gasket 64 of a resilient, sealing material, such as rubber. The groove formed by flanges 60 and 62 opens towards the edge of funnel 56. When cover 36 is closed, the edge of the funnel abuts gasket 64, whereby flanges 60 and 62 lie on either side of the edge. Flange 62, which is the outer flange, is slightly longer than flange 60 and extends downwardly over the upper edge of funnel 56, when the cover is closed, to prevent weather elements from directly hitting the gasket and the edge.

Cover 36 has a lug 66 at one side which supports a pivot pin 76 disposed in a pair of slots 70 of a mounting bracket 72 secured to funnel 56 adjacent the lower portion of the upper edge thereof. Mounting bracket 72 includes a pair of flanges 74 within each of which one of slots 72 is formed, the flanges straddling lug 66. This mounting allows the cover to be moved between an open position, indicated by the dotted lines in FIG. 3, to a closed position as shown in full lines in FIG. 3 and in FIGS. 2 and 4, wherein the cover extends across the open end of funnel 56.

Lever 40 is pivotally mounted on the central outer portion of cover 36 by means of a pivot pin 76 supported by a pair of spaced lugs 78 integral with cover 36. Pivot pin 76 passes through one end of lever 40, the other end of lever 40 being in the form of a handle adapted to be manually actuated. Lever 40 includes a slot or notch 80 engageable with spring 38 and a heel or stop member 82 that engages the top of cap or cover 36, when the cover is closed and locked in position.

Spring 38 is in the form of an elongated irregularly shaped resilient rod whose ends 84 are rotatably supported by a pair of spring retaining channels 86 secured to opposite sides of funnel 56 adjacent the base thereof at diametrically opposed points. Spring 38 includes a pair of arcuate sections 88 that straddle opposite sides of funnel 56, a horizontal cross bar 92 and a pair of straight portions 90 which extend between the adjacent ends of the cross bar and the arcuate portions.

When the cover is locked in a closed position, the cross bar 92 of spring 38 engages the notch 80 of lever 40 and biases lever 40 in a counterclockwise direction, as viewed in FIG. 3, about pivot pin 76 so that stop member 82 is biased against the outer surface of cover 36. The forces imparted to cover 36 by spring 38 acting upon the cover through both the stop member 82 and the pivot pin 76 forces gasket 64 against the edge of funnel 66 so that the gasket is distorted to completely seal the edge of the funnel. Slots 70 permit movement of the cover in a direction normal to the edge of the funnel

whereby the cover is self aligning upon application thereto of the sealing force.

In order to open cover 36, spring 40 is rotated in a clockwise direction, as viewed in FIG. 3, until the spring 38 becomes unstressed so that it can be pivoted away from the notch to its inoperative position, as indicated by the dotted lines in FIG. 3, wherein the upper portion of the spring rests against the upper panel of the sandbox. The initial rotation of the lever 40 disengages stop member 82 from cover 36 and also increases the stress in spring 38 until the line of action passes over the pivot pin whereupon the spring rotates the lever until the spring reaches its unstressed position. After the spring has been disengaged from lever 40, cover 36 is pivoted away from engagement with funnel 56 to its open position, indicated by the dotted lines in FIG. 3. In such position, the cover, along with lever 40, depends downwardly and are spaced from the fill opening of funnel 56 so as not to interfere with filling the sandbox with sand.

To close the cover, the cover is manually rotated from its open position to its closed position. Then, lever 40, if it has already not been positioned, is pivoted to a position where it can receive the cross bar 92 of spring 38. Thereupon, lever 40 is pivoted in a counterclockwise direction. The initial rotation of lever 40 stresses the spring. When the line of force acting on the lever crosses over, the spring causes the lever to snap down into engagement with the cover whereupon the spring effects the necessary seal between the gasket and funnel and locks the cover in place.

It will be thus seen that the invention is easy to operate and the parts can be readily cleaned to prevent sand from interfering with operation thereof. Moreover, the cover is permanently attached to the sandbox and cannot be accidentally removed or lost.

While only a single embodiment has been shown, it will be apparent to those skilled in the art that changes can be made in the details and arrangement of parts without departing from the scope of the invention as defined in the appended claims.

What is claimed is:

1. In sanding apparatus for sanding a rail under a wheel of a railway vehicle, the combination of: a sandbox adapted to be mounted on the railway vehicle and having a fill opening bounded by an annular edge; a cover hinged to said sandbox, said cover being movable between a closed position covering said fill opening and an open position allowing said to be placed in said sandbox, said cover having a circular body and a pair of concentric, axially-extending flanges defining therebetween an annular groove which opens towards said edge; an annular gasket seated in said groove and being engageable with said edge when said cover is closed to exclude from the sandbox external weather elements such as rain, snow and the like; a cover retaining spring pivoted on said sandbox; and a throwover lever pivotally mounted on said cover and being engageable with said spring for locking said cover in said closed position and applying to said gasket via said cover a sealing force. 50

2. Sanding apparatus in accordance with claim 1 wherein said sandbox comprises a funnel which terminates in said annular edge, and said cover and said cover retaining spring are mounted on said funnel.

5 3. In sanding apparatus for sanding a rail under a wheel of a railway vehicle, the combination of: a sandbox adapted to be mounted on the railway vehicle and having a funnel provided with a fill opening bounded by a flat annular circular edge; a cover hinged to said funnel for pivotal movement about a first axis between closed and open positions, said cover having an annular circular groove which opens towards said edge; an annular sealing gasket in said groove engageable with said edge for sealing said fill opening when said cover is closed; a throwover lever pivotally mounted on said cover for movement about a second axis parallel to said first axis between operative and inoperative positions; and a cover retaining spring pivotally mounted on said funnel for movement about a third axis parallel to said first and second axes, said spring being normally unstressed but engageable with said lever so that when said lever is in operative position, said spring locks said cover and applies a sealing force to said gasket. 10 15 20

4. Apparatus in accordance with claim 3 wherein said first axis is located adjacent peripheral portions of said edge and said cover, said second axis is located substantially along a center line of said cover, and said third axis is located at the base of said funnel. 25

5. Apparatus in accordance with claim 4 wherein said funnel is inclined upwardly and said first axis is located adjacent lower portions, so that said cover extends downwardly when in said open position. 30

6. Apparatus in accordance with claim 4 wherein said lever comprises a handle adapted to be manually actuated, a notch engageable with said spring, and a stop member engageable with said cover when said lever is in said operative position. 35

7. Apparatus in accordance with claim 6 wherein said spring comprises an elongated resilient member that extends upwardly along opposite sides of said funnel and across the top of said cover, when said spring is in its stressed position, and through said notch. 40

8. Apparatus in accordance with claim 7 wherein said cover is hinged to said funnel by means including a bracket secured to said funnel and having slot means therein, and a pin secured to said cover and extending into said slot means whereby said first axis is movable along said slot means. 45
